(57) **CLAIM**

The ornamental design for a giraffe novelty, as shown and described.

DESCRIPTION

FIG. 1. Is a left side elevational view of my giraffe novelty with right side elevational view being a mirror image thereof;

FIG. 2. Is a front view thereof;

FIG. 3. Is a rear view thereof;

FIG. 4. Is a top view thereof; and,

FIG. 5. Is a bottom view thereof.

In the drawings, the broken line showing of ears and tail parts depicts environmental subject matter and form no part of the claim.
